(57) **CLAIM**

The ornamental design for a golf hitting mat, as shown and described.

DESCRIPTION

FIG. 1 is a perspective view of a golf hitting mat showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an exploded view thereof;

FIG. 10 is bottom exploded view thereof; and,

FIG. 11 is an enlarged view taken on circle 11 of FIGS. 1. The dash-dot-dash broken lines are included to show the enlarged area and forms no part of the claimed design.
